UNITED STATES PATENT OFFICE.

WILLIAM McCCLAVE, OF SCRANTON, PENNSYLVANIA.

GRATE-SECTION AND FIRE-BED FOR STOVES, FURNACES, &c.

SPECIFICATION forming part of Letters Patent No. 267,910, dated November 21, 1882.

Application filed October 4, 1882. (No model.)

To all whom it may concern:

Be it known that I, WILLIAM McCCLAVE, a citizen of the United States, residing at Scranton, in the county of Lackawanna and State of Pennsylvania, have invented a new and useful Improvement in Grate-Sections and Fire-Beds for Stoves, Furnaces, Heaters, and other Fuel-Burning Structures, of which the following is a specification.

10 My invention consists in certain novel constructions, combinations, and arrangements of parts, whereby an improved vibrating grate-section and also an improved fire-bed formed of sections, all of which move in the same direction, are produced; and my said improvements will be fully understood from the accompanying drawings and the following specification and claims.

15 In the accompanying drawings, Figure 1 is a top view of my improved fire-bed, the horizontal arms of the grate-sections of which it is formed being in their supporting or normal positions. Fig. 2 is a vertical longitudinal section of Fig. 1. Fig. 3 is a similar view to Fig. 25 1, the horizontal arms of the grate-sections being in their abnormal positions, as are also the vertical pendent portions of the said sections. Fig. 4 is a vertical longitudinal section of Fig. 3. Fig. 5 is an end of the grate-section, having its angular form slightly changed and its vertical pendent portion grated, in order to lessen the weight of the section, but in all other respects substantially similar to the grate-sections B B', shown in Figs. 1, 2, 3, and 4; and Fig. 6 is a plan view, showing a stationary grated surface at one end of the grate-frame, which incloses the vibrating grate-sections, the stationary grated surface being a substitute for the movable end grate-section, C, shown 40 in Figs. 2 and 4 as well as in Figs. 1 and 3.

45 A in the drawings may designate the grate-frame at the top of the ash-pit section of either a stove, furnace, heater, or other fuel-burning structure; but this illustration is best adapted for a stove or furnace, inasmuch as the end portion, A', is made with a concave surface on its under side to allow the end grate-section, C, of the fire-bed to move beneath it in the arc of a circle, as shown. Instead of making the under side of the portion A' concave, a rectangu-

lar or other form of recess may be provided beyond and above the lower inner edge of said portion A', and thus room for the grate-section C to swing in back and forward be afforded.

55 The grate-sections B B' are all alike, while the section C is constructed with supporting-arms a, which are shorter than the supporting-arms a' on the sections B B'. The grate-sections B B' are of a form closely resembling a right angle, or more nearly the letter L when it is inverted and its vertical limb is pendent. The top surfaces of the arms a' may be made either curved, as shown in Figs. 2 and 4, or straight, as shown in Fig. 5. The length of 60 the arms a' should be nearly equal to the distance between the journals of the respective pairs of sections, so that a nearly continuous grated fire-bed may be formed when the sections are hung upon their journals c in the 65 grate-frame A and the sections are in their normal positions, as shown in Figs. 1 and 2. The under surfaces of the arms a' may be slightly tapered on their under sides, either on straight or curved lines, so as to give a sharp end to 70 the arms, and at the same time have the greatest bulk of metal near the angle or bend of the sections.

75 The pendent vertical or nearly vertical portions a² of the sections B, B', and C are made 80 preferably solid, and their front and rear surfaces may be formed with any desired curvature, as shown in Figs. 2 and 4, or one surface thereof may be straight up and down, and the other beveled or inclined, as shown in Fig. 5. 85

At the angle or bend of the sections B, B', and C a portion of the metal is removed between each pair of arms a', so as to form a downwardly-beveled surface, b, and at the same time give a knife-edge formation to the section 90 between the arms and some distance below their upper sides. By this construction the descent of ashes between the arms is facilitated and liability of the arms to warp lessened.

95 The portions a² of the sections B, B', and C are respectively of a depth sufficient to nearly close the respective spaces between the respective pairs of journals c of the grate-sections when the arms a' of the sections are vertical, or nearly so, as illustrated in Fig. 4. The depth 100

of the respective portions a^2 may be great enough to lap under the respective sections. The sections at their angle or bend may be rounded or beveled off, and at this point they are made with an increased thickness or body of metal, and on each end of each section the short journal c is provided, as shown. The journals c are preferably placed a little forward of and above a diagonal line of the triangular section, so as to about effect a balance between the weight of the pendent vertical portion a^2 and the horizontal arms a' of the section. This described location of the journals upon which the sections vibrate may be changed so that the journals shall stand on the said diagonal line, as illustrated in Fig. 5; but I believe the location of the journals as shown in Figs. 2 and 4 is far the most advantageous. The vertical or nearly vertical portions of the sections, 20 are provided near their lower edge, at one end, with suitable lugs, d , or equivalent means, and to these lugs a vibrating shaker-bar, d' , is connected as illustrated, or in any other proper manner.

In Fig. 5 the portion a^2 of the section is shown provided with perforations e . By this construction the weight of the section will be lessened, while the function of the portion a^2 will not be materially interfered with. In this view the section is shown with a straight upper-surfaced arm, a' , and a straight and bevel-sided portion, a^2 .

In Fig. 6 the end section, C, of the fire-bed is removed and a stationary grated end portion, 35 E, is applied in its stead, and with this construction all the vibrating grate-sections will be similar to those B B', shown in Figs. 1, 2, 3, and 4, or to the one shown in Fig. 5, inasmuch as it is not necessary to employ a section similar to the one C and have the same turn under the portion A' when the space is 40 filled by the stationary grated surface E, as shown.

The means for vibrating the grate-sections 45 in one direction or the same direction may consist of cog-wheels employed as follows: If two grate-sections are employed to form a fire-bed, the short journal of each section will be extended and a cog-wheel applied fast upon 50 the same, and between the two cog-wheels a loose cog-wheel attached to a shaft of the grate-frame will gear with the wheels of the sections, and the two sections will vibrate in the same direction, and if three grate-sections are employed five cog-wheels would be required—viz., 55 a loose cog between every pair of cogs of the sections.

In operating with my grated fire-bed the sections can be gently vibrated, so as to shake down the ashes; but when it is necessary to 60 cut out a body of ashes, clinker, or other clogging matter from the superincumbent mass of burning fuel the sections are all moved in the same direction in the arc of a circle, which causes them to assume the position shown in 65 Fig. 4, in which position the arms a' stand nearly vertical with full-open spaces between them for the descent of matter above, while the portions a^2 stand horizontal, or nearly so, with the spaces which previously existed between them, as shown in Fig. 2, nearly or quite closed, as shown in Fig. 4, and in which positions these portions a^2 support the mass of fuel until the movement of the sections has been reversed and the arms a' are made to 70 move back through the mass to their normal positions. (Shown in Fig. 2.) The return movement of the sections causes the base portion of the superincumbent mass of matter, consisting of ashes, clinker, cinder, and other débris, to be separated from the upper portion thereof, relieved from its support, and be discharged into the ash-pit.

What I claim as my invention, and desire to 85 secure by Letters Patent, is—

1. The vibrating grate-sections B, each comprising a grated portion, a' , a pendent portion, a^2 , and journals, and forming a fire-bed whose sections all vibrate in the same direction, substantially as described.

2. The grate-sections B B', as constructed, with portions a' and a^2 and with journals, and applied together, whereby the pendent portion a^2 of a section serves alone for closing the space which exists between a pair of sections, 95 substantially as and for the purpose described.

3. The grated fire-bed formed of sections comprising portions a' and a^2 and journals, and all moved in the same direction, substantially as and for the purpose described.

4. The combination of an end grate-section, C, formed with arms a' , and a pendent portion, a^2 , the end bar of the ash-pit section, beneath which the section C vibrates, and a section, B, having a form resembling an inverted L, and all moved in the same direction, substantially as and for the purpose described.

WILLIAM McCALVE.
